UNITED STATES PATENT OFFICE.

CARTER BLATCHFORD, OF CHICAGO, ILLINOIS.

METAL ROOF FOR FREIGHT CARS.

Application filed May 14, 1923. Serial No. 638,841.

To all whom it may concern:

Be it known that I, CARTER BLATCHFORD, a citizen of the United States, residing at Chicago, in the county of Cook and State of Illinois, have invented new and useful Improvements in Metal Roofs for Freight Cars, of which the following is a specification.

This invention relates to improvements in roofs and more particularly to metal roofs for freight cars.

One of the objects of the invention is to provide a metallic roof for freight cars composed of light gage metallic sheets rigidly secured together which is supported by a roof framing so that the light gage metal sheets are relieved of the stresses due to the torsional and weaving movements of the car.

Another object of the invention is to provide a roof composed of a plurality of metal sheets supported at frequent intervals so that light gage material can be used.

Another object of this invention is to provide a metallic roof for freight cars composed of a plurality of sheets secured together and to their supporting carlines which sheets and carlines can be assembled and installed on the car as a unitary member.

In the drawings:

Fig. 1 is a top plan view of a portion of a freight car roof in accordance with this invention, with parts of the roof framing broken away.

Fig. 2 is a section taken along the line 2-2 of Fig. 1.

Fig. 3 is a section taken along the line 3-3 of Fig. 1.

Fig. 4 is a view in side elevation of Fig. 1.

Fig. 5 is a detail view corresponding to Fig. 4 of that portion where the edges of the roof sheets meet and shows the chair supporting the roof sheets at this point.

In this embodiment of the invention the side plates 1 are in the form of Z bars with the upper flanges pointing inwardly upon which rests the ends of the carlines 2, and purlins 3 are supported upon the carlines, as shown in Figs. 1, 2 and 3.

The metal roof sheets 4 may extend from eave to eave or may be made in pairs so that each sheet extends from the eave to the ridge and attached to the adjacent roof sheet on the opposite side of the car in any convenient manner. The abutting transverse edges

of the roof sheets are provided with upstanding flanges 5 which are covered by seam caps 6 in the form of an inverted U having outstanding flanges resting on the body of the roof sheets and secured to the roof sheets by a series of horizontal rivets 7 passing through the cap and abutting flanges.

The roof sheets rest upon the carlines at the ridge and upon the purlins between the ridge and eave. To support the eave end of the roof sheet between the carlines, I have provided plate 8 which extends the length of the car and rests upon the ends of the carlines. Any convenient form of carline may be used. However, in the form shown, the carlines are of channel shape with the web cut away at the end in line with the web of the side plate and the flanges are bent downwardly and riveted to the web of the side plate. The eave supporting plate 8 of the roof sheets is riveted to the upper flange of the carlines and extends outwardly therefrom. The roof sheets are extended beyond the supporting plate and are bent downwardly over the edge to a distance below the upper flange of the side plate.

The flanges 5 of the roof sheets are cut away adjacent the outer edge of the supporting plate and the top of the seam cap 6 is tapered or merged into the plane of its flanges to cover the ends of the roof sheet flanges 5 and the seam cap flange is then bent downwardly over the depending portions of the roof sheets, as shown in Figs. 1 and 3, to form a water tight closure for the seam. The seam of the roof sheets is placed substantially midway between the carlines and chairs 9 are provided between the top of the side plate and supporting plate 8 to strengthen or form additional support for the roof sheet (and the supporting plate) under the roof seam.

The carlines are spaced substantially midway between the seams of the adjacent roof sheets and rest upon and are secured to the side plates at their ends. The roof sheets are further supported by the rigidifying seam caps which extend from eave to eave and are themselves supported at the side plates by the chairs. This combination and construction permits of the use of light gage metallic roof sheets because they are relieved of the stresses due to the torsional and weaving movements of the car, and furthermore, the span of the roof sheets between supports is very small.

This is a continuation in part of my application Serial No. 420,435, filed October 29, 1920.

I claim:

5 In a railway car having side plates, of a metallic roof comprising a plurality of roof sheets spaced apart from said side plates and extending transversely across the car, seam caps positioned above and connecting

the adjacent roof sheets, supporting plates 10 positioned over said side plates and supporting said roof sheets, chairs supporting the roof sheets, seam caps and supporting plates upon the side plate, carlines passing along 15 the center line of each roof sheet and supporting the roof sheet and supporting plate upon the side plate.

CARTER BLATCHFORD

Certificate of Correction.

It is hereby certified that in Letters Patent No. 1,499,337, granted July 1, 1924, upon the application of Carter Blatchford, of Chicago, Illinois, for an improvement in "Metal Roofs for Freight Cars," an error appears in the printed specification requiring correction as follows: Page 2, line 11, claim, after the word "over" insert the words *and spaced from*; and that the said Letters Patent should be read with this correction therein that the same may conform to the record of the case in the Patent Office.

Signed and sealed this 19th day of August, A. D. 1924.

[SEAL.]

KARL FENNING,
Acting Commissioner of Patents.
